AIR COOLER

John D. Scruggs, Phoenix, Ariz., assignor, by direct and mesne assignments, of thirty-three and one-third per cent to himself, thirty-three and one-third per cent to W. F. Vaughn, and thirty-three and one-third per cent to F. R. Draper, all of Phoenix, Ariz.

Application March 18, 1949, Serial No. 82,157

6 Claims. (Cl. 299—24)

1

This invention relates to improvements in air conditioners.

The primary object of this invention is the provision of a compact air cooling or conditioning unit, the water absorbent pads of which have improved means to insure a uniform dispersal of water for efficient cooling action.

A further object of this invention is the provision of an improved air cooling unit having means for the fine dispersal of water upon the evaporating pads.

Other objects and advantages of the invention will be apparent from the following detailed description.

In the accompanying drawing, forming a part of this specification, and wherein similar reference characters designate corresponding parts throughout the several views,

Figure 1 is an end elevation of the improved cooling unit.

Figure 2 is a transverse cross sectional view taken thru the cooling unit substantially on the line 2—2 of Figure 1.

The improved cooling unit A generally comprises a lower casing structure B; upper casing structure C, and a flexible textile sheet D associated between the casing structures B and C for the purpose of insuring fine dispersal of water upon the evaporating pads E.

The casing structure B includes a bottom wall 10, front and rear walls 11 and 12, and side walls 13. The walls 11 and 12 are provided with large passageways 14 therethru for travel of air thru the lower casing structure B.

The pads E are supported between foraminous walls 20 and 21 which may be of screening, or perforated plate material as shown in Figure 1. The drawing in Figure 2 shows three sets of plates 20 and 21. They are secured to the bottom 10, as at 23, and define compartments 24 within which the pad material 22 is disposed. The material 22 may be excelsior, hay, straw, glass wool, or metal wool, etc. A top wall structure 25 may be provided for the casing B; the same having sloping portions 25^a and 25^b in downward convergent relation towards the compartments 24 of the absorbent pad structures, as shown in Figure 2. The side and end walls of structure B are top flanged at 26 and the wall 25 is provided with a similar flange soldered or otherwise secured in leakproof relation with flanges 26. It is to be noted that the entire wall structure 25 within the confines of the flanges 26 lies below the plane of the flanges 26.

The upper casing structure C is mainly a water

2

tank, and of course has the usual filling opening and vent (not shown). It comprises an arched top wall 30 having front and rear flanges 31 and side walls having similar flanges 31. A bottom wall 33 is marginally soldered or otherwise secured in leakproof relation to the flanges 31, as shown in Figure 2, and these walls provide a water compartment 35. A valve 36 is mounted upon the water tank wall 33, having an inlet passageway 37 which outlets at 38 into the compartment 39 between the wall 33 and the porous canvas sheet D. A valve operating rod 40 extends upwardly thru a bearing in the wall 30 and is provided with a regulating knob or handle 41 thereon. It is readily apparent that any type of valve structure 36 can be used for the purpose of regulating the drip of water onto the canvas sheet D. It is to be noted that a relatively thick gasket 45 is provided between the marginal edges of the wall 33 of tank C and the flanges 26 of the bottom casing structure B. The thickness of this gasket determines the capacity of the compartment 39.

The canvas sheet D is of porous material. It may be formed of cotton, nylon or other material, woven or knitted so as to insure the proper degree of dispersal of water therethru. Ordinarily, woven duck or canvas material will suffice and this will enable the water to drip thru the valve structure onto the canvas sheet D. Due to the weave of the latter the water will seep thru the canvas material and form in a film without drops upon the under surface of the canvas. As the weight of the water in the compartment 39 increases the canvas will sag to the contour of the top wall 25, and it will be noted that the water will then have a natural course directly towards the pad compartments 24; the water seeping into the pad compartments, without a dropping action directly onto the padding material which reaches to contact the sagging canvas. Thus the water will be evenly and finely dispersed throughout the pad structure.

It will be noted that no mechanism is provided to force the water into the evaporating pads. I am aware that it has been proposed to drop water into evaporating pads and provide various expedients for the transmission of water into operating pads, such as thru capillary attraction, porous rigid walls, etc. However, to my knowledge no one heretofore has provided a flexible textile sheet for the uniform and efficient transfer of the water uniformly throughout the evaporating pad material.

The valve is adjustable so that the water drip may be regulated to conform to the amount of

air passing thru the air cooler. It can be opened to a degree which will permit the water to enter the space below the canvas above all of the pads; the porosity of the canvas regulating the dripping of the water onto the pads 22.

Any number of the pad racks may be provided.

It is well known to those skilled in the art that the evaporator pads are difficult to keep uniformly moist. Ordinarily this is due to the fact that the water is not properly broken up. The use of canvas woven material has been found by me to provide for a proper distribution of water uniformly thruout the pad structure. The feed of water is entirely by gravity except for the fact that as the air passes thru the lower casing structure, there will be a mild suction thru that portion of the canvas sheet directly at the top of the pad passageway. The canvas sheet need not necessarily touch the entire top wall structure of the lower casing, since this only occurs when there is sufficient weight of water supported by the canvas sheet to accomplish this. Under any conditions the water generally forms in a film, without the formation of drops, upon the under surface of the canvas layer or sheets and provides for a uniform and efficient saturation of the pad material as mentioned.

Various changes in the shape, size and arrangement of parts may be made to the form of the invention herein shown and described without departing from the spirit of the invention or the scope of the following claims.

I claim:

1. A cooling unit comprising a casing structure having an air passageway therethru, providing an air path, perforated means upon the casing structure across the air passageway, relatively thick, water receiving and absorbing pads supported in column formation by said perforated means with their faces of greatest area substantially normal to said path, a water supply reservoir mounted above said pads upon said casing structure including a bottom wall spaced above said pads, a sheet of flexible porous fabric in spaced relation below said wall and above said pads, and means for regulated supply of water onto the top of the porous fabric.

2. A cooling unit comprising a casing structure having an air passageway therethru, providing an air path, perforated means upon the casing structure across the air passageway, relatively thick water receiving pads supported in column formation by said perforated means with their faces of greatest area substantially normal to said path, a water supply reservoir mounted above said pads upon said casing structure including a bottom wall spaced above said pads, a sheet of flexible porous fabric in spaced relation below said wall and in spaced relation above said pads, means for regulated supply of water onto the top of the fabric, and means formed as part of the casing structure in spaced relation below the porous fabric for supporting the latter as it sags to a pre-determined extent, said means being shaped to direct the film of water from the under surface of the fabric directly onto the said pads.

3. In an air cooling unit the combination of a casing structure including a bottom wall, upstanding walls and a top wall, opposed upstanding walls having air entrance and exit passageways therethru, said upstanding walls and top and bottom walls providing a chamber, a series of relatively spaced pairs of foraminous walls extending across said chamber in the path of air travel therethru, absorbent pad material between the said foram-

inous walls of each pair of said walls with their faces of greatest area substantially normal to said path, said top wall having openings therethru to the pad material, a sheet of porous textile material supported by the casing structure above the top wall, and means for distributing water upon the top of said sheet of material for seepage therethru onto the top wall and into the openings thereof onto said absorbent pads.

10 4. An air cooling unit comprising a casing structure including a bottom wall, upstanding walls defining a chamber therein, said upstanding walls having opposed openings therein for travel of air thru the chamber, a series of pairs 15 of spaced foraminous walls across said chamber, pad material in column-like formation between each pair of walls with the faces of greatest area of said pads disposed substantially normal to the path of said air, a top wall for the casing structure downwardly sloping in each direction towards each pad material of each pair of walls, the pad material being exposed upon the casing structure in normally closely spaced relation above the top wall and means for distributing water over the top of the fabric material in such quantity that the material will sag to contact the top wall and convey the water seeping thru said fabric material along the sloping portions of the top wall onto the absorbent pads aforesaid.

5. An air cooling unit comprising a casing structure including a bottom wall, upstanding walls defining a chamber therein, said upstanding walls having opposed openings therein for travel of air thru the chamber, a series of pairs 35 of spaced foraminous walls across said chamber, pad material in vertically disposed column-like formation between each pair of walls with the 40 faces of greatest area of said pads disposed substantially normal to the path of said air, a top wall for the casing structure downwardly sloping in each direction towards each pad material of each pair of walls, the pad material being exposed 45 to the space above said top wall, a porous flexible sheet of material mounted upon the casing structure in normally closed spaced relation above the said top wall, a reservoir supported upon the casing structure above the flexible material having 50 a valve for calibrated feed of water from the reservoir to said flexible material.

6. An air cooling unit comprising a casing structure including a bottom wall, upstanding walls defining a chamber therein, said upstanding 55 walls having openings therein for travel of air across said chamber, a series of relatively spaced pairs of thick absorbent pads disposed parallel in individual upright column formation in said chamber and across said chamber, the top wall for the casing structure having portions thereof which slope in each direction downwardly towards each of the pads and at each side of each pad so that the pads are exposed to the space above said top wall, a reservoir supported by said casing structure above said top wall and in spaced relation therewith, a porous flexible sheet of material mounted between the casing structure and the reservoir spaced closely above said top wall, and means for calibrated flow of water from the reservoir onto the upper surface of said sheet of material, the flexible sheet of material being so spaced with respect to the sloping portions of the top wall that when the sheet of material has a 70 sufficient quantity of water thereon from the sup-

ply received from the reservoir the sheet of material will sag to contact the sloping portions of the top wall so that the water seeping thru the sheet of material will move directly onto the said pads.
